COMBINATION POCKET COMB AND NAIL FILE

Trace Christenson, Jr., Niles, Mich.

Application December 17, 1954, Serial No. 33,598

Term of patent 3½ years

(Cl. D86—8)

FIG. 1.

FIG. 2.

FIG. 3.

FIG. 4.

Fig. 1 is a face view of one face of my combination pocket comb and nail file, showing my new design;

Fig. 2 is a face view of the obverse face thereof;

Fig. 3 is a transverse sectional view taken on line 3—3 of Fig. 2; and

Fig. 4 is a transverse sectional view taken on line 4—4 of Fig. 2.

I claim:

The ornamental design for a combination pocket comb and nail file, as shown.
